[57] CLAIM

The ornamental design for a tractor hood, substantially as shown and described.

DESCRIPTION

FIG. 1 is a left front perspective view of a tractor hood showing my new design;

FIG. 2 is a left side elevational view thereof;

FIG. 3 is a right front perspective view thereof; and

FIG. 4 is a bottom plan view thereof.

The characteristic feature of my design resides in the louvers on the sides of the tractor hood.
